United States Patent Office

Des. 175,492
Patented Sept. 6, 1955

175,492

BLOUSE

Jacqueline Joyce Bassett, West Los Angeles, Calif., assignor to Barco Garment Company, Los Angeles, Calif., a copartnership

Application December 24, 1954, Serial No. 33,667

Term of patent 7 years

(Cl. D3—25)

Fig. 1

Fig. 2

Fig. 3

Figure 1 is a front view of a blouse showing my new design;

Figure 2 is a front view of the garment shown in Figure 1, but with the collar buttoned; and

Figure 3 is a rear view thereof.

I claim:

The ornamental design for a blouse, substantially as shown.

References Cited in the file of this patent

UNITED STATES PATENTS

D. 95,239	Freedman	Apr. 16, 1935
D. 114,757	Geist	May 16, 1939
D. 126,272	Shander	Apr. 1, 1941
D. 166,119	Orloff	Mar. 11, 1952
2,345,764	May	Apr. 4, 1944